CONNECTER PLUG

Samuel E. Guinn, Johnson City, Tenn., assignor
to C. A. Bowman, Annapolis Junction, Md.

Application July 15, 1932. Serial No. 622,766

2 Claims. (Cl. 200—51)

This invention is directed to an improvement in connecting plugs for electric appliances, such as irons or the like, wherein the plug has one end formed to snugly seat in a guard cover surrounding the terminals of the heating circuit in the iron or the like, with the plug having sockets to slidably and frictionally fit over said terminals.

Plugs of this type are subjected to hard usage and frequently become broken due to weakness in structure, this liability to breakage being particularly incident to plugs of this type which in addition to their connecting feature involve the use of a switch by which the circuit may be controlled directly at the appliance.

15 The primary object of the present invention is the provision of a plug of this type made in sections, as is usual, with particular means for confining the sections in plug-forming relation to maintain extreme rigidity of the parts and 20 prevent liability of breakage incident to extreme usage of the plug.

A further object of the invention is the arrangement of the interior parts of the plug to insure their effective operation and insure their 25 complete and effective insulation against breakage during the use of the plug.

The invention is illustrated in the accompanying drawing, in which:—

Figure 1 is a perspective view of the improved 30 plug.

Figure 2 is a longitudinal section, partly in elevation, of the same.

Figure 3 is a plan of the plug with the upper body section removed.

35 Fig. 4 is a detail view of a switch employed in the plug.

Fig. 5 is a detail view of a contact strip with which the switch cooperates.

The plug as a whole is, as is usual in plugs of 40 this type, of relatively flat form, i. e. the plug body 1 has a greater width than thickness. This body is divided longitudinally to present a lower section 2 and an upper section 3, the lower section being designed to carry the circuiting detail and 45 the upper section serving largely as a cover section.

The sections are of course of insulating material and for the particular purpose contemplated are formed to present an instrument engaging 50 end 4 constituting the narrowest and thinnest portion of the plug, a central portion 5 which is of increased thickness and width as compared with the section 4, and a cord terminal engaging end or section 6 which is substantially of the 55 same thickness as the section 5 but of increased

width providing projections 7 to afford a finger grip in handling the plug.

The bottom section 2 of the plug is formed in its uppermost face, or that face with which the cover section 3 cooperates, with a rectangular depression 8 within the enlarged area 5 of such section. The section 2 in that portion included within the part 4 of the plug is formed with spaced, longitudinal depressions 9 opening at their rear ends through the end of the plug and 60 communicating with the central depression 8 at their forward ends. In advance of the depression 8, the section 2 is cut away at 10 to leave a bottom wall 11 somewhat higher than the bottom wall of the depression 8. The section 2 65 in advance of the wall 11 has a semi-annular channel 12, and at the forward end of the plug, i. e. in advance of the channel 12, the section 2 is formed with a semi-circular depression 13 opening through the forward end, the diameter 70 of the depression 13 being less than the diameter 75 of the annular channel 12.

The section 3 is formed with substantially complementary parts, i. e. in the face next the section 2 the rear end of the section 3, i. e. the portion included within the part 4 of the plug, has slight rounded depressions which register with the channels 9 of the section 2 and form therewith circular channels. In advance of the depressions 4 the section 3 is formed with a rectangular depression 15 corresponding to and overlying the depression 8 and forming with the latter an interior rectangular chamber in which the switch operating parts are mounted, as will later appear. The section 3 is also formed with 80 an annular, semi-circular depression 16 registering with and forming with the channel 12 an annular channel when the sections 2 and 3 are assembled.

In advance of the depression 16, the section 95 3 is formed with a semi-circular opening 17 complementary to the opening 13 of the section 2 and forming therewith a central aperture leading into the interior of the plug. The abutments formed by the surfaces 11 of the section 3 are divided by a longitudinal channel 18 extending centrally and longitudinally of the plug and leading to the opening at the forward end. The abutments 110 11 on each side of this channel are formed with wire-receiving depressions 19 extending in opposite directions and leading to the interior 105 conductors 20 arranged at each side of the section 2 of the plug. These conductors 20 which are, of course, metallic have a terminal 21 overlying the bottom 11 of the abutment and secured 110

thereto by a screw 22 serving as a binding screw. From the terminal section 11, the conductors 20 are bent downwardly, as at 23, to overlie end wall of the depression 8 and then longitudinally, 5 as at 24, to bear against the bottom of said depression. The outer edge of the portion 24 is formed near the free end thereof with an upturned ear 25.

Arranged within the circular channels formed 10 by the depressions 9 and 14 are contact sleeves 26 which terminate short of the free ends of the channels and may, if desired, be split longitudinally to insure proper frictional engagement and therefore good contact with the usual plugs of 15 the implement. These contact sleeves extend forwardly of the channels in which they are housed and have split spring ends 27 for switch cooperation. Switch elements 28 are pivotally connected to the ears 25 of the respective conducting strips 20. These switch elements have 20 rearwardly extending knife edge projections 29 designed, when the elements are rocked in one direction, to engage in the split spring terminals 27 of the contact sleeves 26. The switch elements have their upper ends 30 rigidly connected to an insulating block 31, the upper end of which is extended in two directions to provide an indicating surface 32, with the indicating surface centrally provided with an upstanding finger piece 33. The depression 15 in the section 3 of the switch body opens through the upper surface of such section, thereby forming an opening 34 through which the insulating switch block 31, or more particularly the rounded section 32 thereof, together with the finger piece 33, may project in operation. The opening 34 is so formed that in one or the other position of the switch block and switching elements, only one of the surfaces of the section 32 on opposite sides 35 of the finger piece 33 is exposed, and these surfaces are appropriately marked "Off" and "On" to indicate the condition of the switch. The interior formation of the section 3 in advance of the recess 15 is formed to receive the forward 40 portion of the head 32 of the switch block when the switch has been operated to break the circuit, while the rear edge of the opening 34 is formed with a projection 35 to limit the position of the switch.

50 The annular channel formed by the depressions 12 and 16 in the respective sections receives the annular enlargement 36 at the terminal of the usual flexible element 37 through which conductor wires are led and which serves to prevent kinking of the wires adjacent the plug. The formation of the channels 9 in the section 2 leave a longitudinally ranging plane section 38 which abuts against the face of section 3, and these portions of the respective sections are formed, 55 one with a pin 39, and the other with an opening 40 to accurately align the ends of the sections when placing them together.

An important detail of the present invention resides in the means for holding the sections of 60 the plug together and protecting the plug to a material extent against breakage under hard usage. For this purpose, that portion of the plug sections making up the terminal portion 4 of the plug are encircled by a tight fitting metallic band 41. This band completely encircles the 65 body at this point, insures that the sections are

held in accurate and fixed relation, and yet protects the plug against breakage which often occurs in inserting the plug or withdrawing it or from dropping the plug onto a hard surface. The opposite end of each section is formed with a reduced, semi-annular projection 42 which directly encircles the depressions 13 and 17 forming the central entrance to the plug. These projections 42, when the plug sections are assembled, form a circular member at the forward end of the plug and the peripheral surface of this member is formed with a channel 43, in which is secured a split spring ring 44. The ring serves to hold the sections fixedly together against separation and relative displacement at the forward 80 end.

The conductor wires are, of course, extended through the protector 37 and then laterally through the depressions 19 and about the screws 22 of the respective conductors, so that operation 85 of the switch member will make or break the continuity of the circuit to the implement.

If desired, and as preferred, the ears 25 and the cooperating parts of the switch elements 28 may be formed with depressions and projections, 90 indicated at 45, to prevent casual displacement of the parts in either closed or opened switching relation.

I claim:—

1. A connector plug comprising a body including an upper and a lower section, the lower section being formed with a central depression, circular depressions at one side of the central depression and communicating at one end with the latter, abutments provided therein in the opposite direction, contact strips overlying the abutments and seating in the depression, said contact strips having ears, contact sleeves arranged in the circular depressions and extending into the central depression as a split section, knife contacts pivoted between the ears on the contact strips and engaging said split sections of the sleeve, and an insulated bar connecting the knife contacts, said insulated bar having a finger piece extending through an opening in the upper section. 105

120

2. A connector plug formed of two sections, one of said sections having a central depression, an abutment in advance of the depression, circular channels at one side of the central depression and communicating at one end with the latter, sleeve contacts arranged in the circular channels and having split spring ends extending into said depression, contact strips secured to the abutments and having portions resting on the bottom of the depression, and formed with ears, knife contacts pivoted to said contact strips, and an insulated bar connecting the knife contacts, said insulated bar having a finger piece extending through an opening in the upper section, the finger piece having oppositely disposed lateral extensions, the upper section having abutments adjacent the opening walls, engaged by the lateral extensions on the finger piece to limit the movement of the knife contacts, each section being formed at one end with a semi-circular depression, the said depressions together constituting an annular channel to receive the enlarged end of a conductor protector extending beyond the plug. 125
